ASSIGNORS TO TEMPLE CORPORATION, OF CHICAGO, ILLINOIS, A CORPORATION OF
DELAWARE

LOUD SPEAKER CONSTRUCTION

Application filed June 15, 1929. Serial No. 371,243.

Our invention relates to loud speakers, and has among its other objects the production of devices of the kind described which are compact, durable and simple in construction. 5 A particular object of the invention is to provide a loud speaker which can be easily and quickly assembled and in which the parts will remain in perfect alignment even though subjected to hard usage.

10 A preferred embodiment of the invention comprises an improved magnetizing structure having an intense annular magnetic field in which a coil subjected to telephonic currents is positioned, the coil being mounted 15 by improved means to vibrate in the magnetic field and being adapted to impart these vibrations to a diaphragm which is connected to it.

Many other objects and advantages will 20 appear as this description progresses, reference being had to the accompanying drawings, wherein:

Fig. 1 is a central vertical section taken through a loud speaker which embodies the 25 invention.

Fig. 2 is a section taken on line 2—2 of Fig. 1.

Fig. 3 is a section taken on line 3—3 of Fig. 2.

30 Fig. 4 is a perspective view of certain magnet and frame members which form parts of the improved loud speaker, and

Fig. 5 is a perspective view, partly in section, of two pole pieces which form parts of 35 the improved loud speaker.

As set forth above, our improved loud speaker preferably comprises a magnetizing structure. Thus, as shown in Fig. 1, we preferably provide an electro-magnet which com-

40 prises U-shaped magnet members 10 and 11 disposed in opposed relation, the construction being such that the ends of the members 10 and 11 are arranged in pairs. It will be noted that a relatively large aperture 13 is 45 formed in one pair of the opposed ends of the magnet members 10 and 11, and that a smaller aperture 14 is formed through the other pair. Disposed between the members 10 and 11 is a pole piece 15 which is rigidly secured to 50 the members 10 and 11 by a bolt 16, the bolt

16 being screw threaded into the pole piece 15 and being arranged to pass through the aperture 14. It will be noted that the members 10 and 11 are clamped between the pole piece 15 and a washer 18 positioned upon the 55 bolt 16.

Disposed around the pole piece 15 is a winding 20 adapted to energize the pole piece 15 and the magnet members 10 and 11. The front end of the pole piece 15 projects through 60 the aperture 13 and is preferably of reduced diameter. Disposed around and rigidly secured to the front end of the pole piece 15 is a ring 25 formed of non-magnetic material and secured in a recess 26 formed in the ring 65 25 is an annular pole piece 28 which preferably fits snugly in the aperture 13. Obviously, when the coil or winding 20 is energized an intense annular magnetic field exists 70 between the inner pole piece 15 and the annular pole piece 28. Disposed in the annular magnetic field, between the two pole pieces, is an armature or winding 30 carried by an annulus or sleeve 31 which is preferably formed from paper or a phenolic condensation product. The sleeve 31 is preferably provided with a groove 32 to receive the winding 30 and the sleeve 31 is preferably secured in a relatively large aperture 33 formed 75 in a sheet 35, the sheet 35 being formed from 80 any suitable flexible material, such as "formica".

In reality, the sleeve 31 is mounted on the free ends of a plurality of flexible arms 36 formed by stamping slots 37 in the sheet 35 85 (see Fig. 7). The sheet 35 is mounted upon a plurality of bolts 40 which are screw-threaded into apertures 42 provided in the members 10 and 11. (See Fig. 4.)

The above described construction permits 90 the sleeve 31, together with the winding 30, to be displaced longitudinally in the magnetic fields obtaining between the poles 28 and 15. It may be mentioned that a few thousandths of an inch clearance is provided between the winding 30 and the inner surface of the pole piece 28 and a few thousandths of an inch 95 clearance is provided between the inner surface of the sleeve 31 and the outer surface of the pole piece 15.

Secured to the outer end of the sleeve 31 is a conical diaphragm 42 which is preferably formed from paper, or the equivalent, the apices of the cone being cut away and a portion of the diaphragm being bent backwards into the cone to provide an annular flange 43 which is preferably secured to the sleeve 31 by adhesive. The outer edge of the conical diaphragm 42 is secured to an annular flexible member 44 which is preferably formed from relatively thin flexible leather, or the equivalent, the construction being such that the cone 42 and the member 44 together constitute the diaphragm for the loud speaker. The outer edge of the annular member 44 is rigidly secured to a ring 47 stamped from sheet metal, the ring 47 being carried by a plurality of U-shaped arms or brackets 49 which are preferably stamped from sheet metal and have their ends spot-welded to the ring 47. Referring to Figs. 5 and 6, it will be noted that the arms or brackets 49 are secured to the magnet members 10 and 11 by the bolts 40.

The means for securing the outer edge of the annular member 44 to the ring 47 comprises a plurality of bolts 50 which are employed to clamp the annular members 44 between the ring 47 and an annulus 48. An annular member 52 preferably formed of felt, or the equivalent, is preferably secured to the front surface of the annulus 48 by adhesive, or the like, which annular member 52 forms a substantially air-tight joint when the loud speaker is positioned against a baffle.

The loud speaker is preferably supported by bracket or frame members 56 and 57 to which the magnet members 10 and 11 are rigidly secured by the bolts 40 and screws 40^a. The members 56 and 57 preferably comprise upright portions substantially U-shaped in cross-section, flanges 57^a on the upright portions being provided with apertures 57^b for the bolts 40 and the screws 40^a. At the lower ends of the brackets or frame members 56 and 57 outwardly extending flanges 57^c are provided, which flanges are apertured, at 57^d, so that the bracket members may be secured to a suitable support.

A feature of the invention is the employment of the bolts 40 to secure the frame members 56 and 57, the U-shaped bracket members 49 and the sheet 35 to the magnet members 10 and 11. This construction permits the apparatus to be quickly and easily assembled and insures that the several parts will remain in correct alignment.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim

all novelty inherent in our invention as broadly as possible, in view of the prior art.

What we claim as new is:

1. A device of the kind described comprising a pair of U-shaped magnet members disposed in opposed relation, one pair of ends of said magnet members being provided with a relatively large aperture therethrough, and the other pair of ends of said magnet members being provided with a relatively small aperture therethrough, a pole piece disposed between said magnet members and projecting through said relatively large aperture, means projecting through said relatively small aperture for securing said pole piece to said magnet members, a ring of non-magnetic material carried by said pole piece, an annular pole piece carried by said ring and fitting said relatively large aperture, a winding disposed between the first mentioned pole piece and said annular pole piece, a sleeve carrying said winding, flexible means supporting said sleeve, and a diaphragm operatively connected to said sleeve. 75 80 85

2. A device of the kind described comprising a magnet having an annular magnetic field, frame members, a winding disposed in said annular field, a sleeve for carrying said winding, a plurality of flexible arms carrying said sleeve, a diaphragm operatively connected to said sleeve, means for supporting said diaphragm, and common means for securing said frame members, said flexible arms and said supporting means to said magnet. 90 95 100

3. A device of the kind described comprising a magnet having an annular magnetic field, frame members, a winding disposed in said annular field, a sleeve for carrying said winding, a plurality of flexible arms carrying said sleeve, a diaphragm operatively connected to said sleeve, means for supporting said diaphragm, and common means for securing said frame members and said supporting means to said magnet. 105 110

4. A device of the kind described comprising a magnet having an annular magnetic field, frame members, a winding disposed in said annular field, a sleeve for carrying said winding, a plurality of flexible arms carrying said sleeve, a diaphragm operatively connected to said sleeve, means for supporting said diaphragm, and common means for securing said frame members and said flexible means to said magnet. 115 120

In testimony whereof, we have hereunto set our hands, this 17th day of May, 1929.

PAUL G. ANDRES.
FRED W. TEMPLE.
